AUTOMATIC SPACE-PARKING GARAGE

Raymond H. J. Simon, Chicago, Ill.

Application September 25, 1952, Serial No. 311,382

2 Claims. (Cl. 214—16.1)

1

My invention relates to automatic space-parking garages.

An important object of my invention is to provide a garage of the aforementioned character which is liftable in a vertical direction to the extent of one or more floors, or stories.

Another object of my invention is to provide a garage of the aforementioned character which has several floors loadable from the street level.

A still further object of my invention is to provide, in connection with a garage of the aforementioned character, hydraulic lift means which will operate outside of the confines of the garage to provide access to the upper floors thereof for loading and unloading automobiles.

A still further object of my invention is to provide, in a garage structure of the aforementioned character, turntable means on each floor thereof to distribute and place the cars on each floor in the most expedient space-saving arrangement.

A still further object of my invention is to provide foolproofing safety means on the said turntable means so that cars will not accidentally run off the said turntable means.

A still further object of my invention is to provide electrical control means for the operation of the said turntable means, which is accessible from the driver's seat of an automobile and which is positioned on the said turntable means and accessible at arm's length.

A still further object of my invention is to provide hydraulic means for lifting a garage structure one or more floors.

A still further object of my invention is to provide automatic locking means associated with the said garage structure for locking the said lift means in position when it reaches a particular floor.

A still further object of my invention is to provide monitor board means, or indicator means, associated with lighting means on each and every floor; the said lighting means being positioned over each and every car stall available on the floor, so that the monitor board may be utilized for spotting and notifying an operator on a particular floor, by lighting the light over the respective car that that particular car is being called for, simultaneously notifying the operator on the floor that the lift is approaching, so that the operator may have the car ready on the turntable means available to be moved onto the lift platform for lowering and delivery to the customer.

A still further object of my invention is to provide door opening means which is electrically

2

operated, so that the same will be maintained opened when moving cars in and out of each respective floor.

A still further object of my invention is to provide switch means which will operate the door means to each and every floor simultaneously, controlling the hydraulic means which operates the lift.

A still further object of my invention is to provide secondary switch means for controlling the hydraulic means which lifts the building one or more floors.

A still further object of my invention is to provide foolproofing means, including electromagnetic solenoid locking means to lock the switch means controlling the lift, when the switch means controlling the garage lifting operation is actuated, and vice-versa.

A still further object of my invention is to provide a novel structure possessing the foregoing characteristics, which is simple and foolproof to operate.

Other objects and advantages inherent in my invention will become apparent from an examination of the accompanying drawings, bearing further elucidation in the ensuing description, wherein like symbols designate like parts, and in which;

Fig. 1 is a perspective view of my invention with certain portions thereof cut away in order to more clearly depict the operative structural details thereof.

Fig. 2 is a longitudinal sectional view, to reduced scale, indicating the hydraulic systems for lifting the garage building, and for raising the hydraulic automobile lift means.

Fig. 3 is a view similar to Fig. 2 showing the garage building in raised position and the lift at ground level.

Fig. 4 is a plan view of one of the floors in the building showing the means of access thereto through the hydraulic lift platform.

Fig. 5 is a front view of the locking mechanism utilized in order to maintain the lift platform in alignment with each respective floor.

Fig. 6 is a cross-sectional view taken, substantially, on the lines 6—6 of Fig. 5.

Fig. 7 is a transverse cross-sectional view taken, substantially, on the lines 7—7 of Fig. 5.

Fig. 8 is an enlarged illustration of the turntable means shown partly in section in order to illustrate the transmission or driving mechanism thereof.

Fig. 9 is a sectional view taken, substantially, on the lines 9—9 of Fig. 8.

Fig. 10 is a cross-sectional view of the brush

and commutator means employed to afford connection to the manually controlled turntable switch means.

Fig. 11 is a diagrammatic view showing the electrical connections employed in my invention.

Fig. 12 is an enlarged electrical diagrammatic view showing the locking means for the lift that is positioned on each floor adjacent the base of each doorway thereof.

Referring to Fig. 1, it will be seen that my invention, which is generally designated 13, comprises a building 14 made up of structural elements such as guide rails 24 operating slidably in fixed rails 23 secured to the pilings 22 embedded below the surface of the soil to afford proper rigidity therefor; the said guide rails 23 being connected by a series of vertical struts 29 and reinforced by angle irons 30. Any other suitable structural method may be employed for the erection of the building 14. The outer portion of the building 14 is preferably of concrete, and each floor is enclosed as indicated at 25 and provided with a number of glass block illuminating windows 26. There are a number of upper floors designated 15, 16, 17 and 18 which are accessible through the lift platform 36, which is operated by virtue of a hydraulic piston 37 being suitably connected to a hydraulic mechanism which will be hereinafter described in detail, and which operates in a hydraulic well 38.

The doorways of the floor 15 are provided on the sides with door enclosures 27 in which doors operate slidably from each side in order to close the doorway 15, and close the same completely. On each doorway there is a locking means 28, which will be later described, and which operates in concert with a suitably mortised opening on the lift platform 36 so as to hold the same in positive locking engagement while the cars are being loaded or unloaded from the floors 15, 16, 17 and 18.

The lower floors 19 and 20 are each considered street level floors, structure deemed to be an important feature of my invention; namely, that the lower floor 20 may be lowered to the position shown in Fig. 2 by the hydraulic means which is indicated; the floor 20 may be raised to the level indicated in Fig. 3 so that automobiles 66 could be loaded therein from the street level through door 65. After the floor 20 is filled with cars, the building is lowered to the position indicated in Fig. 2 and then cars are loaded into the confines of the floor 19. Thus, the garage building affords more than one street level floor of operation which facilitates the parking and delivery of cars parked for short duration or during rush hours. The remaining floors are accessible through the lift platform 36.

It will be seen that in the said platform a telescopic piston structure 47 and 37 is operated by hydraulic means 48 in the well 38 through the agency of a hydraulic motorized pumping unit 53 which receives its supply through the pipe 51 connected through the elbow 52 to the pumping unit 53 which in turn is connected to the piping 54; the control or check valve 55 connected to the piping 56, the elbow 57 and the piping 58 to furnish the inlet of oil below the bottom 49 of the piston 37 so as to cause it to be lifted. The oil is exhausted through the piping 59 connected through elbows 60 and 62 and the piping 61 and 63 with a control valve 64 in order to govern the operation thereof. The pumping unit 53 is provided with telescopic piston structure 47 equipped with piston rings 50 to operate sealably in the

bore of piston 37. The building 14 is lifted or lowered in order to make the floors 19 or 20 accessible to street level 21 by means of hydraulic pumping means 93 which is connected to furnish an inlet through piping 147, control valve 148, piping 149, elbow 99 and piping 49, so as to cause the piston 34 to rise. The oil is exhausted from the well 35 through the connections of nipple 41 connected to elbows 42 and 44 intermediately connected by nipple 43, in turn connected to piping 45, and provided with a discharge valve 46 so as to regulate the system to operate to the desired speed and afford proper hydraulic cushioning for the operation.

Thus, it can be seen that cars 67 will be elevated by means of the lift platform 36 to be positioned in whichever upper floor 15, 16, 17, 18 it may be desired through the operation of the hydraulic system hereinbefore described. On each floor, reference being had to Figs. 4 to 9, it will be noted, same as on the floor 15, illustrated in Fig. 4, that a turntable means 31 is provided. The said turntable means will receive the cars from the lift platform 36 and then radiate to the proper position so as to place the cars 67 in the most desirable parking stall, and at the same time compactly place cars on the floors 15 evenly distributed thus using the space most economically. On each floor there is a locking system, which is of an electromagnetic nature, designated 28. The said locking system comprises an enclosure in which are mounted the electromagnets 69 interconnected by the strut 70 which holds firmly the locking latch 71 which operates in the opening 68 and enters the opening 72 of the lift 36 whenever the magnets 69 are energized, thus, furnishing a safety means for cars to be driven in to be parked on the floor.

Each turntable 31 is equipped with safety means 33 to hold a car thereon to prevent the same from running off the platform as illustrated in Figs. 8, 9 and 10. The same consists of a rotatable platform 73 which is driven by the motor 62 fastened to the spider 63 located in the well 84 of the floor 18. A ring gear, or an annular gear 85 is secured in the well 84 and held stationary. The pinion 87 on the motor 62 drives an intermediate gear 86 which is pivoted to idle on stub-shaft 88 so that the turntable 73 is caused to be motivated. The motor 62 is electrically connected to the commutator rings 88 which are insulated one from the other, and which are contacted by electric brushes 91 urged into contacting relationship by means of the spring 92 and secured to the support 90 which in turn is anchored to the turntable means 73. The connections from the brushes 92 to the switch 32 are indicated at 142 in Fig. 4. Thus the wheels of an automobile 74, when driven onto the platform, will enter first to run on the apron 80 resting on the floor 15 and pivoted at 143, which allows the wheels 74 to travel forward. The bumper 75, in advance of the wheel 74, will cause the plate 76 to be motivated to the dotted position by virtue of its articulate connection at 77. The plates 76 and 80 are interconnected by linkage 79 articulately connected at 78 to the lug 81. Thus, when the plate 76 is motivated from its normal position in full lines to the dotted lines shown in Fig. 8, it will pull along behind the rear bumper of an automobile, the plate 80, hence when the brake is put on the entire affair will be rigidly held in place on the turntable 73, allowing it freedom to be rotated to proper alignment with a particular stall in which the automobile is to be parked.

The electrical diagrams are illustrated in Figs. 11 and 12; the electromagnets 69 as seen in Fig. 12 are operated to cause the bolt 71 to enter the recess 72 in the lift 36 by means of electrical wiring connections 115 and 116; 116 going to the source of supply 94 in turn connected to the switch element 104, and connected also to the branches 109, 110, 111 and 112 for respectively operating the locking means on the floors 15, 16, 17 or 18. The switch 104 is in neutral position at 113, and in reverse position at 114. Thus, when the switch 104 is operated to move the lift platform 36 to a particular floor, it will also actuate the proper bolt 71 to enter the recess 72 in the lift platform. The hydraulic means 53 is electrically connected to the switch 104. The switch means 98 is connected to the prime mover 94 and is connected through the lines 97, 96 and 95 to the hydraulic pumping means 93 and returned through the connection 144, 145, and 146, the connection is brought back to the source of supply 94. The electromagnetic solenoid 107 is connected to the switch element 98 by means of the electrical connection 141 and connected to the switch 98 and through the connection 102 going to the switch 104 and also connected through line 97 back to the solenoid 107 which is provided with bifurcated locking core 106 to engage the locking tail 105 of the switch 104 and lock the same the engagement when the circuit is closed by means of the switch 98. Thus, each switch will operate to nullify the action of the other and vice-versa.

The bus bars 122 are connected through line 121 to contacts 124 which close the circuit through contacts 125 which ride on doors 122 and are connected through line 126 to lines 127, 128 to the source 94 whereas lines 121 are connected through lines 120 and 103 to switch 104. Switch 104 has its optional terminals 109, 110, 111 and 112 connected through line 102 and the reverse terminal 114 through lines 129 and 130 back to form the circuit to the source 94. When the switch 104 is motivated the solenoid 108 will be energized causing bifurcated locking core 100 to engage locking tail 99 of switch 98 rendering the same ineffective electrically or immobile. The switch 98 is connected to the source of supply 94 through line 119, line 97, 96 to hydraulic pumping unit 93 and back to the source 94 through lines 144, 145 and 146. The solenoid 108 is connected by lines 101, 102, 103 to switch 104.

The door means 123 is provided with contacts 124 operating on a bus bar circuit 122; the other contact being indicated at 125. Contacts 125 are connected through the wiring 126, 127, and 128 to the source of supply 94 and the bus bar structure 122 is connected through the wires 120 running to the line 103 and to the switch 104. Thus the doors are simultaneously operated when the switch 104 is operated when it contacts one of the points 109, 110, 111 and 112 for selectivity of the upper floors. The pumping unit 53 has its return connected to the source of supply 94 by means of the electric line 118.

A monitor board, or indicator board 131 is also provided on the main floor which has as many buttons as there are automobiles placed on each respective floor. Each button 132, 133, 134 and 135 corresponds to lamp 132', 133', 134' and 135', each positioned over a stall on the floor where cars are to be parked, and each button is connected to its corresponding lamp as illustratively indicated for lamp 135'; button 135 is connected to lamp 135' by means of lines 137 and 138 connecting to the button 135 and 75

through connection 140 running to the source of supply 94, lines 136, 137, 138 and 140 indicating the circuit of the button 135 to the lamp 135'. Thus, if car located or parked under the light 135' is desired, the button 135 is depressed on the board 131, the operator on that particular floor will notice the light go on or flash, which will be his signal to take that car and drive it onto turntable 31, wait until the doors 123 slide open, at which time the lift will approach to alignment with the floor so that the car may be driven off by the operator onto platform 36.

It will be noted that the switch means 32 is so positioned as not to interfere with the driving of a car onto the turntable 31, yet to permit the driver of the car to actuate the said switch means for controlling the rotation of the turntable means 31 without it being necessary for him to leave the car; in other words, it can be done from the driver's seat.

In actual operation during the rush hours, the parking will be done most effectively on floors 19 and 20. Loading the floor 20 first from the street level 21 and then lowering the building by the switch means and hydraulic means heretofore described, subsequently, loading the platform 19; during the day when parking is not required as frequently, the cars will be parked by means of the lift platform 36 on the floors 15, 16, 17 and 18 through the controls and means heretofore described.

Although I have herein described rather succinctly the nature and use of my invention so that persons skilled in the art will have no difficulty apprising themselves of the teachings thereof and, inasmuch as the disclosure is susceptible of various alterations, modifications, and improvements, I hereby reserve the right to all modifications, alterations, and improvements falling within the scope and spirit of my invention, as well as any modifications that are embraced suggestively in the accompanying drawings, and any that may come within the purview of the foregoing description; my invention is to be limited only by the appended claims.

Having thus described and revealed my invention, what I claim as new and desire to secure by Letters Patent is:

1. Automatic space-parking garage, comprising a liftable building structure including a multiple number of upper stories and plural number of lower floors, guide rail means vertically positioned outside of and secured to the said liftable building structure, fixed rails anchored below ground level and reenforced by architectural enclosure, the said guide rail means being slidably operable within the confines of the said fixed rails, primary hydraulic means for lifting and lowering the said liftable building structure, door means on each of the said upper stories, automobile lift platform operating adjacently the said door means and outside the confines of the said building structure and used primarily to carry a single vehicle from the street level to any of the said upper stories so as to permit transfer therebetween, and secondary hydraulic means for raising and lowering the said automobile lift platform to alignment selectively with any of the said upper stories the building in its normal lowered position having the uppermost of the lower floors aligned with street level so that vehicles may be driven thereon directly from the street level, the remaining lower floors also being alignable with the street level, the horizontal dimensions of each lower floor

and of each upper story being a multiple of the length and width of the said lift platform.

2. Automatic space-parking garage, comprising a liftable building structure including a multiple number of upper stories, and plural number of lower floors, guide rail means vertically positioned outside of and secured to the said liftable building structure, fixed rails anchored below ground level and reenforced by architectural enclosure, the said guide rail means being slidably operable within the confines of the said fixed rails, primary hydraulic means for lifting and lowering the said liftable building structure, door means on each of the said upper stories, automobile lift platform operating adjacently the said door means and outside the confines of the said building structure and used primarily to carry a single vehicle from the street level to any of the said upper stories so as to permit transfer therebetween, secondary hydraulic means for raising and lowering the said automobile lift platform to alignment selectively with any of the said upper stories the building in its

normal lowered position having the uppermost of the lower floors aligned with street level so that vehicles may be driven thereon directly from the street level, the remaining lower floors also being alignable with the street level, the horizontal dimensions of each lower floor and of each upper story being a multiple of the length and width of the said lift platform, and turntable means centrally disposed on the floor of each of the said upper stories.
